COLLAPSIBLE TUBE

Rudolph M. Sanders, Brooklyn, N. Y.

Application June 28, 1939, Serial No. 281,616

18 Claims. (Cl. 221—60)

The invention relates in general to collapsible containers and dispensers of the type now used for containing and dispensing semi-fluid substances like tooth paste, paints, and other merchandise.

The primary object of the invention is to provide an improved form of such containers which can be constructed economically both in the amount of material used and in the labor involved and which at the same time will provide sufficient structural strength to maintain its configuration until intentionally collapsed in the act of ejecting its contents.

Still another object of the invention is to provide an axially collapsible tube form of container which during its entire period of use will be provided with a flat base to maintain the tube in upstanding position and which both initially and at least during the early stages of its use will provide a smooth outer face adapted to contain printing or to which may be affixed a label and in this way maintain exposed for practically the life of the container advertising matter, directions and other printed matter usually found on tubular containers of this character. In general the invention features the providing of a collapsible container which while permitting distortion in the sense of permitting collapsing in the direction of its axis will resist irregular or messy mutilation and thus tend to present a more pleasing form of package than has been known heretofore.

Various other objects and advantages of the invention will be in part obvious from an inspection of the accompanying drawing and in part will be more fully set forth in the following particular description of one form of container embodying the invention, and the invention also consists in certain new and novel features of construction and combination of parts hereinafter set forth and claimed.

In the accompanying drawing:

Fig. 1 is an enlarged view partly in axial section of a collapsible container illustrating a preferred embodiment of the invention in its initial distended form;

Fig. 2 is an enlarged sectional view of the bottom portion of the container when finally collapsed;

Fig. 3 is an axial view of a portion of the cylinder wall of a modified form of the invention taken on the line 3—3; and

Fig. 4 is a transverse sectional view taken on the line 4—4 of Fig. 3.

In the drawing and referring first to the show-

ing in Fig. 1, there is disclosed a container 10 formed primarily of two parts, a body 11 and a closure cap 12. The body 11 is of tubular form and preferably formed of a flexible and comparatively non-resilient material and is of cylindrical form with an inclined top wall 13 and threaded neck 14 adapted to receive the conventional form of closure cap. The lower end of the cylinder 11 is provided with an outwardly extending flange 15.

It is a feature of this disclosure that the outer face 16 of the cylinder body 11 is smooth and designed to be printed or stamped with printed matter usually found in structures of this character. Projecting inwardly and integrally from the cylinder or body 11 is a rib 17 of spiral form extending from end to end of the cylinder. While the rib 17 is illustrated as formed integral with the cylinder wall, it is obviously within the scope of the invention to form the rib as a separate spring and attach it as by welding or other means to the inner face of the cylinder 11, or even to leave it unattached.

Referring to the closure cap 12 it is preferably formed as a stamping, and includes an outlining annular ring 18 forming a bottom for the container considered as a whole. The outer edge of this flange is provided with an extension 19 which is inturned and laps about the outstanding flange 15 to secure the cap 12 rigidly to the body 11. The central portion of the cap 12 is pressed upwardly to form a cylindrical portion 21' and reduced therefrom to form an inverted cup 20, the side wall 21 of which is of annular form and spaced inwardly from the adjacent side of the cylinder 11 to form an annular recess 22 of a size sufficient in length to receive all, or, substantially all, of the collapsed wall as shown in Fig. 2.

Referring to the modified showing of the cylinder 23 in Figs. 3 and 4, the spiral rib 17 of the Fig. 1 and Fig. 2 showings, has been replaced by a series of inwardly extending projections or ribs 24 which are arranged in vertically spaced apart planes, that is, planes spaced along the axis of the body portion which axis is indicated by the line a—b. Considering the projections in any one plane, it is noted from the showing in Fig. 4 that the ribs, in that case two in number, are circumferentially spaced apart and in this particular instance are spaced 180° apart with plain arc or uncorrugated regions 25 therebetween. It is also noted from the showing in Fig. 3 that each rib in any one plane is located opposite the uncorrugated portions 25 between the cor-

responding ribs in the next adjacent plane or planes.

As these inward projections from the column provided by the cylinder walls constitute reinforcements to the walls, it follows that the walls themselves need not have the structure strength to resist distortion as they would necessarily have to possess if these reinforcing elements were absent. It is therefore possible to effect a saving in the amount of material used in forming the cylinders to minimize the cross sectional area of material used perhaps even to the point where the tube per se would not have sufficient structural strength to maintain its own configuration when in use. However, the reinforcing ribs irrespective as to whether they may be of the spiral form shown in Figs. 1 and 2, or the annular ring-like form or portions of circles shown in Fig. 3, are apt to supplement any inherent weakness in the tube and provide in the completed structure a form of container which will possess sufficient structural strength to function in its intended capacity, not only as a container but also as a means for ejecting its contents through the opening in the throat when pressure is applied to the closure cap.

In operation and referring first to the disclosure in Figs. 1 and 2, it will be understood that when pressure is applied to cause the bottom formed by the cap 12 to approach the open top the spiral rib progressively collapses and in effect functions as would a metal spring of similar contour. As the spring-like rib 17 collapses, it will, of course, tend to expand radially which means that each turn of the spring will tend to break down the initial columnar form of the portion of the wall between the turns of the spiral rib and in this way there will be a tendency to avoid localizing the collapsing of the tube to any portion thereof and the general effect will be a gradual shrinking in length of the tube considered as a whole.

Referring to the operation of the forms of tube shown in Fig. 3, substantially the same action takes place except that in these cases the collapsing of the tube takes place in succeeding planes of action, the bottom area contracting axially before there is any noticeable contraction in the uppermost planes and particularly with reference to the showing in Fig. 3, the outer face of the tube is maintained in its initial smooth condition for a longer period of use than is possible with the present known forms of similar container.

I claim:

1. A merchandise container and dispenser including a tubular wall collapsible in the direction of its axis in ejecting its contents, and having an outer printing face adapted to provide a smooth surface to receive printing, stamping, or a label, said wall provided with a spirally formed reinforcing integral rib projecting inwardly from the inner face of the wall and adapted to be collapsed axially and to distend radially during the axial collapsing of the tubular wall and acting in its radial distention to break down the initial columnar form of the portions of the wall between the turns of the spiral rib.

2. A container including a tubular wall collapsible in the direction of its axis and having a circularly continuous outer face adapted to provide a smooth printing surface, said wall provided with an integral rib extending at an angle to the axis and coacting with an adjacent por-

tion of the wall to provide sectional areas of material of different thicknesses at the line of intersection of the wall with an axial plane.

3. A container including a tubular wall collapsible in the direction of its axis, having an outer face free of projections to form a smooth surface and provided with a spiral spring engaging the inner face of the wall and acting to break down the columnar form of the wall as it is collapsed.

4. A container including a tubular wall formed primarily of a single thickness of material and reinforcing means engaging one face of the wall and coacting therewith to provide the necessary structural strength to the wall to maintain its configuration, said means being collapsible with the wall in the direction of its axis and acting on the wall during collapsing to corrugate the wall.

5. A collapsible container including a tubular wall having a plurality of thickened portions forming inwardly projecting ribs having convex inner faces, said ribs arranged in lines contained in planes spaced apart axially of the tubular wall, the ribs of each line being circumferentially spaced apart, and the ribs of each line offset circumferentially from the ribs of the next adjacent line thereby to stagger the ribs.

6. A container including a tubular body having a wall with long portions of greater thickness of material than the portions of the wall therebetween and said portions being in circumferentially spaced apart relation and in planes spaced apart axially of the tubular body and each portion being of elliptical form when considered in the plane in which it is contained.

7. A container including a tubular body collapsible in the direction of its axis and the wall of which is initially of cylindrical form and provided on its inner face with thickened portions to form the wall, of undulatory form along a straight line defined by the intersection of the wall by an axial plane and also of undulatory form along a closed line defined by the intersection of the wall with a plane perpendicular to the axis one end of the body being free of said thickened portion and thus of cylindrical form having an outstanding flange defining said end, a preformed base having a cylindrical portion fitted in said cylindrical end of the body, said base provided with an outstanding flange forming a wide-spreading ring-like support for the container and in engagement with the flange on the body and an extension from the base flange overlapping the outstanding flange on the body.

8. A one-piece tube collapsible in the direction of its axis and provided with a line of spaced apart solid ribs additional to the material outlining the tube and contained in a plane perpendicular to said axis.

9. A container including a tubular body collapsible in the direction of its axis and provided with a plurality of ribs additional to the material forming the tubular body portion integral with and projecting from the tubular body and spaced apart thereon both axially and circumferentially.

10. A container including a tubular body collapsible in the direction of its axis and provided with a horizontal outstanding flange defining its lower end, a cap for closing the lower end of said body including an annular ring forming a support for the upstanding body, the outer edge of the ring being turned in lapping engagement with the flange to secure the cap to the body,

the central portion of the cap projecting integrally upwardly from the inner edge of the ring into the interior of the body and providing therewith an annular space adapted to receive the lower portion of the body when collapsed into the same.

11. A container including a tubular body collapsible in the direction of its axis, having a smooth outer surface, a reinforcing element at its inner face extending at an angle to the axis of the body, a cap for closing one end of the body and providing between itself and the adjacent end of the body an annular groove adapted to receive at least the adjacent ends of the body and element when collapsed towards the cap. 10

12. A merchandise container including an easily collapsible upstanding body portion initially of cylindrical form and thus free of corrugations and a bottom closure providing a flat broad based support for the body portion in its succeeding collapsed positions, and said body portion provided with means integral therewith for controlling the form into which the body portion may be collapsed when subjected to axially directed compression forces. 15

13. A merchandise container including an easily collapsible tubular body portion of non-elastic material, the outer surface of the body portion being initially smooth and said body portion provided on its inner face with an inwardly extending integral projection. 20

14. A merchandise container including an easily collapsible tubular body portion of non-elastic material, the outer surface of the body portion being initially smooth and said body portion provided on its inner face with a plurality of integral extensions spaced apart lengthwise of the body. 25

15. A merchandise container including an easily collapsible tubular body portion of non- 30

elastic material and a spiral spring within the body portion and engaging the inner wall thereof.

16. A merchandise container including an easily collapsible tubular body portion initially smooth on its outer side prior to being collapsed and means on the inside thereof additional to the material forming the tubular body portion and acting thereon during axial collapsing of the container to cause the body portion to collapse in accordion fashion.

17. A merchandise container including an easily collapsible tubular body of non-elastic material provided at one end with an outstanding flange, a cap for closing said end of the body, said cap including a portion of cup-like form intruded into the body and with a portion thereof fitting in said end of the body, and said cap also including an annular ring forming a flat bottom to the container and extending in a plane perpendicular to the axis of the body, said annular ring provided with an extension overlapping the outstanding flange of the body. 20

18. A merchandise container including an easily collapsible tubular body of non-elastic material provided at one end with an outstanding flange, a cap for closing said end of the body, said cap including a portion of cup-like form intruded into the body and with a portion thereof fitting in said end of the body, and said cap also including an annular ring forming a flat bottom to the container and extending in a plane perpendicular to the axis of the body, said annular ring provided with an extension overlapping the outstanding flange of the body, said cap providing a wide spreading base for supporting the container in an upstanding position and having a lap joint connection with the outstanding flange of the body. 25
